(57) **CLAIM**

The ornamental design for a percussive therapy device, as shown and described.

DESCRIPTION

FIG. 1 is a front perspective view of a percussive therapy device.

FIG. 2 is a right side elevation view of the percussive therapy device.

FIG. 3 is a left side elevation view of the percussive therapy device.

FIG. 4 is a front elevation view of the percussive therapy device.

FIG. 5 is a rear elevation view of the percussive therapy device.

FIG. 6 is a top view of the percussive therapy device.

FIG. 7 is a bottom view of the percussive therapy device; and,

FIG. 8 is a front perspective view of the percussive therapy device with a movable handle in an open position for two-hand use.

The broken lines shown in the drawings are for the purpose of illustrating portions of the percussion therapy device, which form no part of the claimed design.

1 Claim, 8 Drawing Sheets
